UNITED STATES PATENT OFFICE

90,800

DESIGN FOR A JIG-SAW PUZZLE BLANK

Earle S. Cascadden, Lapel, Ind.

Application March 2, 1933. Serial No. 47,382

Term of patent 7 years

To all whom it may concern:

Be it known that EARLE S. CASCADDEN, a citizen of the United States, residing at Lapel, in the county of Madison and State of Indiana, has invented a new, original, and ornamental Design for a Jig-Saw Puzzle Blank, of which the following is a specification.

Reference is made to the accompanying drawing in which the single figure is a plan view of a

jig-saw puzzle blank, showing my new design. The article has no material or appreciable thickness.

I claim:

The ornamental design for a jig-saw puzzle blank, as shown and described.

In testimony whereof I affix my signature.

EARLE S. CASCADDEN.
